CLAIM

The ornamental design for a curb protector for roof drains, as shown and described.

DESCRIPTION

FIG. 1 is an isometric view of a first embodiment of our curb protector for roof drains, illustrating our new design;

FIG. 2 is a cross sectional view taken along line 2—2 of FIG. 1;

FIG. 3 is a front elevational view of FIG. 1;

FIG. 4 is a rear elevational view of FIG. 1;

FIG. 5 is a side elevational view of FIG. 1; the other side view being a mirror image thereof;

FIG. 6 is a top plan view of FIG. 1; and,

FIG. 7 is a bottom plan view of FIG. 1.

The broken line showing of a curb in FIG. 1 for illustrative purposes only, and forms no part of the claimed design.
